DESIGN FOR A PEDESTAL FOR A STATUETTE OR SIMILAR ARTICLE

James G. Davis, Buffalo, N. Y.

Application July 27, 1933, Serial No. 48,844

Term of patent 14 years

To all whom it may concern:

Be it known that I, JAMES G. DAVIS, a citizen of the United States, residing at Buffalo, in the county of Erie and State of New York, have invented a new, original, and ornamental Design for a Pedestal for a Statuette or Similar Article, of which the following is a specification, reference being had to the accompanying drawing, forming part thereof.

In said drawing:

I claim:

The ornamental design for a pedestal for a statuette or similar article substantially as shown.

JAMES G. DAVIS.
